UNITED STATES PATENT OFFICE.

EDWARD W. ALLEIGH, OF MINNEAPOLIS, MINNESOTA.

MACHINE FOR ORNAMENTING WOOD, &c.

SPECIFICATION forming part of Letters Patent No. 400,625, dated April 2, 1889.

Application filed August 7, 1888. Serial No. 282,145. (No model.)

To all whom it may concern:

Be it known that I, EDWARD W. ALLEIGH, a citizen of the United States, and a resident of Minneapolis, county of Hennepin, and State of Minnesota, have invented new and useful Improvements in Machines for Ornamenting Wood and other Compressible Material, of which the following is a specification, reference being had to the annexed drawings, illustrating the invention, in which—

Figure 1, Sheet 1, is a perspective representation of a machine for ornamenting wood in which is embodied my invention; Fig. 2, an elevation of the rear portion of Fig. 1, 15 showing the gearing; Fig. 3, Sheet 2, a vertical sectional elevation of Fig. 1, or so much thereof as to include its upper portion and a portion of the feed-roller on line α , including the die. Fig. 4 is a horizontal section of 20 Fig. 1 on line α , looking down.

The purpose of the present invention is to provide better means for imprinting on wood or other compressible material with roller-dies; and its nature will be better understood 25 by reference to the following description.

A represents a strong cast-iron bed portion to the machine, and B B represent standards, which are cast solid to the bed, and also made rigid to a projecting portion, X, (more clearly 30 shown at Fig. 3,) to serve as a support and housing for the gearing b c. The inner sides of the standards B B are provided with grooves, in which ribs K K on the supporting portion Q of an arm, C, have a vertical reciprocating movement. The means to attain this 35 movement consist of a screw, I, on which is placed a gear-wheel, c, with a screw-thread formed through it to engage the screw I, and further consist of a gear, b, smaller than gear 40 c, and pivoted to the portion X, so as to be turned by a forked lever, F. The opposite end of arm C from Q is provided with a depending portion, D, whereby the shaft E, which supports the die Y, has bearings in the 45 portions Q D and the die has sufficient space above to turn.

The bed A is provided with a table, D, on which the material to be imprinted is placed, and projecting a little above said table and

lying in it is a feed-roller, G, Figs. 1 and 3, 50 which carries the material to turn the roller-die to make the imprint.

Any suitable gearing may be employed to drive roller G; but because considerable power is required and accuracy is necessary 55 I employ as most suitable a drive-wheel, V', which is on a shaft, Z, extending through the bed A.

On shaft Z is a gear, V, which meshes into a gear, W, the latter gear being affixed to the 60 same shaft as the feed-roller G, so that when the wheel V' is driven at the proper speed the material, Q', to be imprinted will be properly fed to the die Y, which at Fig. 3 is partly shown in elevation and partly in section, and 65 in position for use.

A machine constructed as herein shown and described has been in practical operation for some months, and it is found that the standards B B, cast solid to the bed A and rigidly 70 secured at their top portions by the support X, in connection with the arm C, provided with the depending guide portion Q and the depending portion D, provide a better support for the shaft E and die Y than machines 75 of any other construction, and that the support X and gearing b c therein is very desirable means for regulating the height of the arm C in its adjustment to bring the die Y properly to the wood, Q'. 80

I claim and desire to secure by Letters Patent of the United States—

In machines for ornamenting wood, the arm C, provided with the depending guide Q, carrying the ribs K K and the depending portion 85 D, and each depending portion provided with a bearing for the shaft E and the die Y thereon, in combination with bed A and standards B B at the sides of the guide portion Q, with grooves therein to engage the ribs K, the table 90 D', and roller G, projecting through it; the screw I, gears b c, and lever F, as and for the purpose specified.

EDWARD W. ALLEIGH.
